UNITED STATES PATENT OFFICE.

THOMAS E. McNULTY, OF SAN FRANCISCO, CALIFORNIA.

TUBULAR STEEL DESK-FRAME.

1,291,976.

Specification of Letters Patent.

Patented Jan. 21, 1919.

Application filed May 3, 1918 Serial No. 232,268.

To all whom it may concern:

Be it known that I, THOMAS E. McNULTY, a citizen of the United States, residing at San Francisco, in the county of San Francisco and State of California, have invented certain new and useful Improvements in Tubular Steel Desk-Frames, of which the following is a specification.

This invention relates to a tubular steel construction for the frames of school desks and includes novel means for attaching the back, seat and desk to said frame so that all three, viz. the back, seat and desk, are adjustable relative to the frame and to each other.

The tubular frame construction is not only durable but is strong and sanitary, and the various adjustments allow the fitting of each desk to the size of the particular pupil to whom it may be assigned. In case of reassignment the proper adjustments can be readily made to accommodate the new pupil.

The invention also includes the novel features of construction and operation herein-after described, pointed out in the claims, and shown in the accompanying drawings, in which:

Figure 1 is a side elevation, looking toward a seat and the back of a desk.

Fig. 2 is an end elevation.

Fig. 3 is a side elevation of the rear of the desk, the seat and seat back being removed.

Fig. 4 is a detail view of a seat back hanger plate.

Fig. 5 is a section through the desk, broken out.

In constructing the desk as shown I employ a metal tubular A-shaped frame 1, one being provided for each end of the desk, each frame having a curved bow portion 2 at the top and suitable foot portions 3 at their lower ends. Each frame 1 is also provided with two cross braces 4 welded or brazed to the frames. A tubular cross piece 5 detachably connects the bow portions of the two frames.

A lower tubular member 6 connects the two upper crosspieces 4. Extending between the tubular cross members 5 and 6 are seat back supporting bars 7, the lower ends of the bars being angled as at 8 to engage the tubular member 6. These bars are provided with suitable openings 9 and support the seat back members 10. The back pieces are

adjustably connected to the bars by means of plates 11 secured to the backs and provided at their upper ends with hook members 12 to engage the openings 9. After the proper adjustment of the back pieces have been made they are locked in such adjusted position by a bolt and nut, as at 11a.

A seat 13 provided with end castings 14 is mounted between brackets 15, the brackets 15 being V-shaped and having sleeves 16 at their ends that slidably engage rear members of the frame 1. To support and adjust the seat, arms 17 are extended from the upper ends of the brackets 15 and through said arms loosely pass adjusting screws 18. The arms 17 rest on and are supported by nuts 19 and lock nuts 20 are placed on the screws above the arms. A scale in inches and fractions thereof is laid off on the rear members of the frame 1, as at 21, and by turning the nuts on the screws 18 the seat can be adjusted the desired number of inches above the floor to accommodate the pupil using the seat.

An extension desk top 22 is provided with cleats 23 adapted to slide in guides 24 carried by pressed steel side members 25. These side members carry semi-cylindrical brackets 26 adapted to bear and slide on the front members of the frame 1, being clamped thereto by screw and nut as at 27.

A brace 28 connects each side member 25 with its bracket 26.

Vertical adjustment of the desk by sliding movement of the brackets 26 along the frame 1 is provided for by securing U-shaped plates 29 to the side members, said plates partially embracing the frame 1. Blocks 30 are secured to the plates and in the blocks I mount a threaded shaft 31. This shaft passes through a block 32 secured to the desk back, 22a, and the shaft 31 is oppositely threaded on opposite sides of the block 32. An end of the shaft projects and is squared, as at 33, to receive a wrench. Thread blocks 34 having pins 34a are mounted on the shaft on opposite sides of the block 32. Links 35 are pivoted respectively to said pins and to plates 37, as at 36, which plates are secured to the frame 1. On rotation of the shaft 31 the thread blocks 34 will be moved along it, thereby raising or lowering the links 35, according to direction of the travel of the blocks, thus raising or lowering the desk, the plates 29 and brackets 26 sliding on the frame 1.

The links also aid in supporting the desk in adjusted position.

It will be noted therefore that I provide a very simple frame for the desk, seat and backs, all of which are adjustable to suit the needs of the pupils.

The desk is light and strong in construction, is economical in the use of material, meets all sanitary requirements, and is hygienic in its operation.

What I claim is:—

1. In a desk, tubular A-shaped frames, a tubular member connecting the apices of the frames, cross pieces carried by the frames, a tubular member connecting said cross pieces and in the vertical plane of the first mentioned tubular member, a seat vertically slidable along said frames, a desk also movable along said frames, bars connected to the first mentioned tubular member and angled to engage the second mentioned tubular member, and seat back members adjustably supported by the bars.
2. In a desk, A-shaped end frames, cross pieces for said frames, a cross piece connecting the apices of the frames, a lower

cross piece supported by cross pieces of the frames, a desk supported by the front members of the frames, a seat supported from the rear members of the frames, bars connected to the cross piece connecting the apices of the frames and to the cross piece supported by the cross pieces of the frames, and seat backs supported by said bars.

3. A desk frame comprising A-shaped end frames, each frame having cross pieces, upper and lower frame connecting members, the upper one being secured to the apices of the frames and the lower one to a cross piece of each frame, depending bars hung from the upper connecting member and having their lower ends angled inwardly to engage the lower connecting member, means for adjustably securing a seat back to the bars, a seat slidably mounted on the frames and below the bars, and a desk slidably mounted on the opposite sides of the frames from the back and seat, with independent means for sliding the seat and back along the frames, as and for the purpose set forth.

In testimony whereof I affix my signature.

THOMAS E. McNULTY.
